UNITED STATES PATENT OFFICE

109,169

DESIGN FOR A MIRROR

Della Halbert Whitehead, Del Rio, Tex.

Application December 30, 1937, Serial No. 73,984

Term of patent 14 years

To all whom it may concern:

Be it known that Della Halbert Whitehead, a citizen of the United States, residing at Del Rio, in the county of Val Verde and State of Texas, has invented a new, original, and ornamental Design for a Mirror, as shown in the accompanying drawing and described in the following specification.

The figure is a perspective view of a mirror, showing my new design.

I claim:

The ornamental design for a mirror as shown.

DELLA HALBERT WHITEHEAD.
